UNITED STATES PATENT OFFICE.

ROBERT W. JAMIESON, OF ROCHESTER, NEW YORK.

GEARING.

SPECIFICATION forming part of Letters Patent No. 620,074, dated February 21, 1899.

Application filed January 17, 1898. Serial No. 666,941. (No model.)

To all whom it may concern:

Be it known that I, ROBERT W. JAMIESON, of Rochester, in the county of Monroe and State of New York, have invented certain new and useful Improvements in Gearing; and I do hereby declare the following to be a full, clear, and exact description of the same, reference being had to the accompanying drawings, forming a part of this specification, and to the reference-numerals marked thereon.

My present invention relates to angle-gearing, and particularly to that class embodying wheels or disks having pins or rollers projecting from the face thereof approximately parallel with the axis of rotation—such, for instance, as shown in my Patent No. 596,884, dated January 4, 1898; and it has for its object to improve and simplify their construction, whereby light rollers and supporting pins may be employed without sacrificing strength; and to these ends it consists in improvements hereinafter described, the novel features being pointed out particularly in the claims at the end of this specification.

In the drawings, Figure 1 is an elevation of a pair of gears constructed in accordance with my invention; Fig. 2, a similar view looking from the right side of Fig. 1, with a portion of one gear broken away to show the engagement of the rollers or teeth; Figs. 3 and 4, detail sectional views of modifications.

Similar reference-numerals indicate similar parts.

The gearing embodies two wheels or disks 1, rotatable on axes 2, arranged at an angle relatively, each disk having projecting from its face a series of pins 3, secured in any suitable manner, as by inserting them through apertures in the disks and upsetting their ends, or, if desired, the pins might be threaded and secured by nuts. Mounted loosely upon the pins 3 are the rollers 4, constituting the engaging surfaces or teeth of the gears, said rollers being each preferably a truncated sine conoid or solid of revolution described by the peripheries or engaging surfaces of the coöperating rollers or teeth on the other wheel. The outer ends of the pins 3 are connected to fingers 5, formed integral with a ring-plate 6, rigidly secured to the face of the disks 1 by

rivets 7, as shown, or otherwise. In the preferred construction the ring-plate is in contact with the face of the disk close up to the base of the rollers, and the fingers extend upwardly away from the disk and parallel with the pins 3, and the upper ends are bent over substantially parallel with the disk and being perforated are secured to the pins by passing the latter through the perforations and spreading their outer ends or otherwise. From this construction it will be seen that comparatively light pins 3 may be employed for the rollers, both ends being firmly held and braced against lateral strain, and as the disks 65 may be made of cast metal and the plate of stamped steel the cost of the gear will be comparatively slight.

Instead of extending the fingers on the ring-plate 6 at right angles to the face of the disk, as in Figs. 1 and 2, I may extend them at an angle, as in Fig. 3, or, if desirable, the outer portion of the disk 1, on which the roller-pins are secured, may be offset, as in Fig. 4, for half the height of the rollers, and the fingers 75 on the plate 6 may be correspondingly shortened and secured to the face of the disk, as before described.

The faces of the rollers are so curved and correlated that they will coöperate to transmit power from one gear to the other with the minimum amount of friction, a receding action, and a uniform ratio of velocity, and by reason of the efficient support given to the outer ends of the pins the latter may be made 85 of comparatively light material without liability of being bent, which bending would of course impair the perfect coöperation of the rollers on the engaging wheels.

While this form of gearing may be employed 90 for various purposes, it is particularly adapted for use on so-called "chainless" bicycles by reason of its lightness and simplicity of construction.

It will be understood that while the wheels 95 are shown with their axes arranged at right angles the relative angle could be changed somewhat without materially affecting the operation, and, further, that while it is desirable to have the rollers rotate on their axes in a 100 plane substantially parallel with that of the wheel on which they are mounted, as shown,

they might be arranged at a slight angle there-to without departing from the spirit of my in-vention.

I claim as my invention—

- 5 1. In gearing, the combination with two wheels with their axes arranged at an angle relatively, each wheel having a series of pins on its face, a series of conoidal rollers rotatable on the pins, and a plate rigidly attached to the face of the wheel having fingers extending upwardly and outwardly therefrom and secured to the ends of the roller-pins, the rollers on the said wheels engaging successively to drive either wheel from the other.
- 15 2. In gearing, the combination with two wheels with their axes arranged at an angle relatively, each wheel having a series of pins on its face, a series of (conoidal) rollers rotatable on the pins and a plate rigidly attached

to the wheel having the fingers extending outwardly and secured to the ends of the pins carrying the rollers, the rollers on said wheel engaging successively to drive either wheel from the other.

3. In gearing, the combination with two wheels with their axes arranged at an angle relatively, each wheel having a series of pins on its face, a series of rollers rotatable on the pins and a plate rigidly attached to the wheel having the fingers extending outwardly and secured to the ends of the pins carrying the rollers, the rollers on said wheel engaging successively to drive either wheel from the other.

ROBERT W. JAMIESON.
